UNITED STATES PATENT OFFICE.

NATHAN M. LOWER, OF PITTSBURGH, PENNSYLVANIA, ASSIGNOR TO LOCOMOTIVE STOKER COMPANY, A CORPORATION OF PENNSYLVANIA.

STOKER.

Application filed September 27, 1924. Serial No. 740,167.

This invention relates to stokers, and more particularly to the mechanically operated type.

One of the objects of the invention is the provision of means for operating the fuel-delivering vanes together with new and improved means for cushioning the forward movement thereof.

Another object of the invention is the provision of new and improved means for operating the vanes whereby a single resilient member is utilized for operating a plurality of vanes in one direction.

A further object of the invention is the provision of new and improved means for timing the movement of the various parts so that a minimum amount of fuel is delivered in the path of the receding vane.

A still further object of the invention is the provision of new and improved means for operating and for varying the action of the vanes.

Other and further objects and advantages of the invention will appear from the following description, taken in connection with the accompanying drawings, in which

Fig. 1 is a front elevation of the stoker showing one of the distributing vanes extended forwardly and in section, and showing the power shaft in section on line 1—1 of Fig. 4;

Fig. 2 is a section on line 2—2 of Fig. 3;

Fig. 3 is a vertical section of a portion of a locomotive and stoker showing my invention in position thereon;

Fig. 4 is a section on line 4—4 of Fig. 3;

Fig. 5 is a plan view of the device, with parts in section and parts broken away;

Fig. 6 is a section of a detail;

Fig. 7 is a section on line 7—7 of Fig. 3; and

Fig. 8 is a sectional plan view of a detail.

For convenience the invention will be described as applied to a locomotive. It is understood, however, that its use is not limited to locomotives or confined to any particular type of fire-box.

On the drawings the reference character 10 designates the fire-box of a railway locomotive, 11 the back wall thereof, and 12 the fire door opening, all of which may be of the usual or any approved construction.

The ^{stoker} mechanism comprises the conveyor or fuel transferring member 13 of any approved construction. That shown is in the

form of a conveyor screw 14, rotatably mounted in the casing 15 and trough 16, in the usual manner. The screw 14 is operated from the motor or engine 17 through the chain drive 18, power shaft 19 and gears 20, 21 and 22, in the gear box 23 located at the rear end of the trough 16. The front end of the casing 15 is enlarged, as at 24, to provide sufficient space for receiving the fuel from the return conduits 25 and 26, as will presently appear, and is connected to the elevator casing 27 by the universal joint 28.

Fuel is transferred from the tender by the conveyor 13 to the casing 27, in which it is elevated by any suitable mechanism.

As shown, the elevator 29 is in the form of a screw. The upper flight of the screw is formed into a flat portion 30, which is adapted to be flush with the top of the distributor plate 31. The fuel delivered by the elevator 29 to the flat portion of the screw and the distributor plate 31 is projected into the fire-box 10 of a locomotive by the oscillating vanes 32 and 33, the one scattering it over the left and the other over the right portion thereof. Suitable means are provided for rotating the elevator 29 in timed relation to the operation of the vanes, where-

by either portion 30 will be in its forward position when the other vane is advanced. In order that the amount of fuel delivered by the elevator in rear of either vane during its forward movement be a minimum, the elevator operating means is so constructed

that the elevator will rotate at different speeds and will be rotating at its minimum rate during the movement of either vane.

Any suitable mechanism may be employed for this purpose. As shown, the elevator 29 is operated by elliptic gears in a manner that will now be described.

The lower end of the shaft 34 of the elevator 29 is provided with an elliptic gear 35, which meshes with the corresponding elliptic gear 36 on the countershaft 37. The shaft 37 is provided with a bevel gear 38, which meshes with the corresponding bevel gear 39 on the power shaft 19, whereby said elevator is operated from the motor 17. A suitable housing 41, having the extension 42, is provided for enclosing said gears. By means of this arrangement the elevator 29 rotates very slowly during the operation of each of the vanes, and consequently the

amount of coal that is moved rearwardly by the vanes as they are retracted is small and does not interfere with the operation of the vanes. The coal moved rearwardly falls 5 into the pockets 42 and 43, and is returned by the conduits 25 and 26 to the casing 24.

The increased size of the casing 13, as well as the increased diameter of the upper end of the conveying screw 14, will accommodate 10 any coal that may be returned through the conduits 25, 26.

Suitable means are provided for operating the vanes 32 and 33. As shown, the shafts 44 of the vanes are provided with 15 pinions 45, which are adapted to be oscillated by rack bars 46 and 47 mounted in suitable guides 48. The rack bars 46, 47, are moved inwardly for causing the fuel-throwing vanes to be swung forwardly by a 20 spring 50, the ends of which are suitably connected to the inner ends of the rack bars 46, 47. The spring is so constructed and its length is such that the tension of the same will be relieved an instant before the vanes 25 reach their limit of forward movement, whereby the final forward movement of the same will result in compressing the spring to a certain extent. Thus the spring 50 will cause the vanes to swing forwardly and will 30 also cushion their forward movement. This is considered an important feature, since it relieves the vanes of considerable strain incident to change in direction of movement of the parts. The rack bars are moved outwardly for retracting the vanes by suitable mechanism, one form of which will now be 35 described.

Pivoted to the rack bars 46, 47, as at 49 and 51 (see Figs. 1 and 7), are the rack 40 actuating levers 52, 53, which are pivoted, as at 54, 55. The lever 52 is provided at its upper end with a curved surface 56, which is adapted to be engaged by laterally extending contact members, as the rollers 57 45 and 58, carried by a rotating disc 59 for retracting the rack bar 46, as will presently appear. A curved lever arm 61, pivoted as at 62, has its upper end in engagement with the lever 53, as by means of a flanged roller 50 or wheel 63. The lever arm 61 is adapted to be engaged by the contact members 57, 58, for forcing said arm into engagement with the lever 53 for moving the same outwardly to retract the rack bar 47. A spring 55 60, between the arm 61 and link 56, is adapted to withhold said arm from the actuating lever 53, its inner surface remaining in the path of the contact members 57, 58, whereby said arm will not interfere with the inward movement of the lever 53 and the consequent forward movement of the vanes 32.

The rack bars 46 and 47 are held in retracted position by any suitable mechanism, such as the spring-pressed dogs or latches 64, 65, which are adapted to engage in the re-

cesses 66, 67, in the said bars 46, 47, respectively.

The disc 59 may be rotated by any approved mechanism. As shown, it is operated from the shaft 19 by the sprocket chain 70 68, which engages sprockets on said disc and a sprocket wheel on said shaft, as clearly shown in Figs. 1 and 7.

It is desirable that means be provided for feeding uniformly to all parts of the grate 75 area, or for trimming the fire at either side of the fire-box, as occasion may require. In the form of the device selected to illustrate an embodiment of the invention, means have been provided whereby the fireman may 80 cause the vanes 32, 33, to operate alternately or selectively, as desired. This is accomplished by controlling the tripping of the dogs or latches 64, 65.

The latch 64 is provided with a tripping 85 arm 71, and the latch 65 with a tripping arm 75, taking the form of a lever pivoted, as at 77, and its load end 76 being connected by a link 78 to the latch, as shown through the medium of a crank arm 81 extending from 90 the hub of the latch. The arms 71, 75, are tripped by means of radially slideable bars 72, 73, carried within suitable casings 83, 83, mounted on the disc 59, springs 85, 85, holding them normally in retracted and hence 95 inactive positions. Cams 86 and 91, formed on a rotatably adjustable sleeve 87 mounted on a hub 88 of the disc 59, engage the inner ends of the bars 72 and 73, respectively, to force them outward at suitable intervals to 100 effect the tripping action.

The swell of the cam 86, which cooperates with the bar 72, extends almost entirely around the sleeve, while the cam 91, which cooperates with the bar 73, is short and is 105 located opposite the flat or inactive portion 89 of the cam 86. For the normal operation of the stoker the cams are positioned as shown in Fig. 7, and the bar 72 trips both arms 71, 75, during each complete rotation 110 of the disc, the bar 73 being retracted as it passes each arm. By shifting the sleeve 87 to bring cam 91 opposite the arm 71 and the flat portion of cam 86 opposite arm 75, the 115 vane with which the latter is associated will remain at rest while the other vane will be actuated twice during each rotation of the disc. By shifting the sleeve to bring cam 91 opposite arm 75 and the flat portion of 86 120 opposite arm 71, the latter and its associated vane remain inactive and the arm 75 will be tripped by both bars 72, 73.

Suitable means are provided for adjustably turning the sleeve 87, whereby the cams 86 and 91 may be shifted for controlling the 125 tripping of the latches 64, 65. As shown, the sleeve 87 is provided with a pinion 92, which is adapted to be engaged by a rack bar 93. The rack bar 93 is held in position by suitable means, as the roller guide 94. 130

The rack bar 93 is adapted to be reciprocated by a manually operated lever 95, and held in adjusted position by said lever in the usual manner.

5 I claim as my invention—

1. In a stoker, a distributor plate, means for supplying fuel to said distributor plate, a pair of vanes operating in a plane substantially parallel with said plate, means including one spring only for impelling both of said vanes forwardly for throwing said fuel from said plate.

2. In a stoker, in combination, a pair of swinging fuel-delivering vanes operating about independent axes, means including one spring only for moving said vanes, said spring being adapted to move each vane in one direction, and means for tensioning said spring.

20 3. In a stoker, in combination, a fire-box, a pair of swinging vanes mounted to operate about independent axes, means for moving said vanes forwardly for supplying fuel to said fire-box, said means, including one spring only for cushioning the forward movement of said vanes.

4. In combination, a stoker, a fire-box provided with an opening, a distributor plate in said opening, a pair of swinging vanes for sweeping fuel from said plate into said fire-box, a variable speed elevator for delivering fuel to said plate, means for operating said vanes in timed relation to the operation of said elevator; and means for operating said elevator, said means being adapted to operate said elevator at its minimum speed during the movement of said vanes.

5. In combination, a stoker having an opening in one wall thereof, a distributor plate in said opening, distributor means for projecting the fuel from said plate into said fire-box, a variable speed elevator, means for operating said distributor means intermittently, and means for operating said elevator, said means being adapted to operate said elevator at its maximum speed during the inactive period of said distributor means.

6. In combination, a stoker, a fire-box provided with an opening, a distributor plate in said opening, a pair of swinging vanes for sweeping fuel from said plate into said fire-box, a variable speed elevator for delivering fuel to said plate, means for operating said vanes in timed relation to the operation of said elevator, means for operating said elevator, said means being adapted to operate said elevator at its minimum speed during the movement of said vanes, and conduits for receiving the fuel swept rearwardly by the return movements of said vanes.

7. In a stoker, a distributor plate, a pair of swinging vanes for sweeping fuel from said plate, a single spring for operating said vanes, said spring being adapted to move

each vane in one direction, and cam means for operating said vanes in the opposite direction.

8. In a stoker, a distributor plate, a pair of swinging vanes for sweeping fuel from said plate, a single spring for operating said vanes, said spring being adapted to move each vane in one direction, and cam means for operating said vanes in the opposite direction, said spring being adapted to cushion the forward movement of said vanes.

9. In a stoker, a pair of swinging vanes, means for alternately operating said vanes, a variable speed elevator for delivering fuel in the path of said vanes, and means for operating said elevator and vanes in timed relation.

10. In a stoker, a pair of swinging vanes, rack bars for operating said vanes, a spring connected to said rack bars for moving the same, said spring being adapted to move each bar in one direction, and means including rotating contact mechanism for moving said bars in the opposite direction.

11. In combination, a distributor plate a variable speed screw elevator for delivering fuel to said plate, the upper flight of the screw terminating in a flat plate flush with said distributor plate, means for rotating said elevator at minimum speed while said flat plate is in its foremost position, a pair of swinging vanes for sweeping the fuel from said plates, and means to swing one of said vanes forwardly while said elevator is turning at minimum speed.

100 12. In a stoker, a pair of swinging vanes, means including rack bars for operating said vanes, a spring connected to said rack bars, means for moving said bars to tension said spring, latches for holding said bars with said spring under tension, and manually controlled means for releasing said latches.

110 13. In a stoker, a pair of swinging vanes, rack bars for operating said vanes, spring means for moving said bars in one direction, a rotating disc, contact members on said disc, means including a pair of levers and a lever arm for engaging said contact members for moving said bars to tension said spring means, latches for engaging said bars, means for tripping said latches, and manually actuated cam means for controlling said tripping means.

120 14. In a stoker, a distributor plate, a variable speed screw elevator for delivering fuel to said plate, a pair of swinging vanes for sweeping the fuel from said plate, and means for alternately or selectively operating said vanes in timed relation to the rotation of said screw elevator.

125 15. In combination, a fire-box having an opening therein, a distributor plate extending into said opening, a rotary elevator for delivering fuel to said plate, a pair of swinging vanes for projecting the fuel from

said plate into said box, means for operating said elevator at variable speed in timed relation to the operation of said vanes, means for operating said vanes, and means for controlling the frequency of the operation of each of said vanes.

tary elevator for supplying fuel to said plate, a pair of vanes for sweeping said fuel from said plate, means including one spring only for operating said vanes, said spring being adapted to project said vanes forwardly alternately. 10

16. In a stoker, a distributor plate, a ro-
